PACKAGING METHOD

Robert W. Gries, Neenah, and Bennie A. Rafoth, Appleton, Wis., assignors, by mesne assignments, to American Can Company, New York, N. Y., a corporation of New Jersey

Application July 31, 1956, Serial No. 601,275

2 Claims. (Cl. 53—32)

This invention relates to a substantially sealed package and its method of manufacture, the package being particularly adaptable for the packaging of a semi-hard extrudable material exemplified by ice cream, but also adaptable to the packaging of other and varied products.

In the present state of the art, ice cream, for example, is ordinarily packaged in relatively thick and stiff printed paperboard containers bearing a waxed coating. The substantial quantity of paperboard material required in the manufacture of these rather heavy containers necessarily results in a substantial cost factor in the packaging medium.

The principal purpose of this invention is to provide a package requiring materially less packaging material, which can be readily printed for identification and waxed or otherwise coated for leakproofness of the package, with closure of the package by means which will result in a substantially leakproof container. Further objects and advantages of this invention will be made clear in the following description and explanation of the drawings, in which:

Figure 1 is a plan view of a series of the paperboard blanks which comprise one element of the container to be formed.

Figure 2 is a schematic layout of the steps involved in the packaging method.

Figure 3 is a perspective view of the completed package showing an initial stage of the opening thereof.

Figure 4 is a perspective view similar to Figure 3, but showing a further step in the opening of the package, and

Figure 5 is a perspective view showing the package in completely opened condition.

The complete package of this invention involves two packaging elements, a paperboard blank, which, while relatively stiff, may be of a lightness and thickness not presently in common use in packaging, and a thin, flexible sheet, such as waxed paper, foil, plastic film or the like, to provide liquid proofness. The paper sheet or wrapping may be printed for purposes of identifying the product to be contained in the package. We prefer to use a blank with a thickness of about .009 inch or less, and a paper sheet of about .0025 inch, which compares with a thickness of .017 to .026 inch for the paperboard presently used in the average ice cream carton.

In a preferred method of manufacturing our package, the paperboard blanks are separated from a continuous roll. The paper outer wrapper in this preferred method also is separated from a continuous roll thereof, successive independent wrappers being severed from the roll by conventional means as the packaging process is carried out.

Figure 1 shows a succession of our paperboard blanks as they would be supplied in the preferred method of packaging. As shown in Figure 1, an individual blank 1 includes a front panel 10, main panel 11, rear panel 12, cover panel 13 and opening flap 14 consecutively hinged together along perforation or score lines 15, 16,

17 and 18. Main end flaps 19 and 20 and cover end flaps 21 and 22 are respectively hinged to panels 11 and 13 along perforation or score lines 23, 24, 25 and 26. Lines 25 and 26 provide a definite weakness in the blank, 5 for a purpose explained later.

Blank 1 may be attached to a blank 2, consisting of similar elements, along lines of weakness 27 and 28, these lines of weakness preferably comprising very heavy perforations. However, these lines of weakness are not 10 essential to separation of the blanks during the packaging operation. With similar reference numerals, blank 2 comprises panels and flaps 110, 111, 112, 113, 114, 119, 120, 121 and 122 separated by perforation or score lines 115, 116, 117, 118, 123, 124, 125 and 126. Similarly, 15 blank 2 may be separated from a next successive blank 3, shown partially cut away in Figure 1, by lines of weakness 127 and 128.

Figure 2 is a schematic layout of the method involved in forming our package. A series of blanks as 20 described above in connection with Figure 1 is fed from a roll 30, being carried by conventional conveyors not shown and guided and fed by rollers indicated at 31. Consecutive blanks are severed by conventional means, such as a knife 32, at a first station of operation A. 25 The thus-separated independent blanks are at the next succeeding station B formed into a receptacle having open ends and top. In this position, with additional reference to Figure 1, the main 11 and cover 13 panels are erected perpendicular to rear panel 12, the remaining panels and flaps being carried therealong in their original relationship. The open ends of the receptacle may if desired 30 be closed by elements of the receptacle-forming means. At this stage, the receptacle is below a filling head 33, through which the required amount of material to be 35 packaged may be deposited in the receptacle.

In the packaging of ice cream, to which our invention 40 is particularly suitable, the ice cream 4 may be extruded through head 33 in a semi-hard condition, the consistency being such as to maintain the product in its extruded form. Head 33 is of course of size essentially commensurate with the dimensions of the blank panels, so that a 45 substantially perfect fit of the extruded material within the receptacle is obtained. It is obvious that suitable and conventional means may be used to sever from the extruded material the proper amount to be deposited in the receptacle for packaging. After the material is 50 extruded into the receptacle formed as just described, the partially formed package proceeds to a station C where the end flaps 19 and 20 are closed over the open ends of the receptacle, thence to station D where the end flaps 21 and 22 are folded to overlie flaps 19 and 20, and then to station E where front panel 10 is folded over 55 to close the open top of the receptacle.

The package may then be turned to lie upon its cover panel 13, as at station F, and thence moved by conventional conveying means to station G, at which point the operation of applying the previously-described outer wrapper commences.

60 The independent outer wrappers, one of which is identified by reference numeral 40 in Figure 2, may be separated from a continuous roll 41, and may be printed with suitable indicia to identify the packaged product. The independent wrappers are severed from the roll by conventional means such as knife 42, not necessary to be shown here in detail.

In our preferred method of forming the package, the 65 filled receptacle at station G is brought upwardly against wrapper 40 in such fashion that one end portion 43 of the wrapper overlies the front panel 10 of the blank-receptacle as at station H. The wrapper is then pressed completely around the receptacle, with an intermediate stage shown at station I. The wrapper 10 is of pre-

determined dimension so that when the wrap-around operation just referred to is completed at station J the other end 44 of the wrapper will extend slightly beyond opening flap 14, so that this other end of the wrapper may be heat-sealed to the exterior surface of the wrapper adjacent the first end 43 in the position shown at station J. As this wrapping around operation is completed, the opening flap 14 of the blank-receptacle is automatically pressed to overlie front panel 10 with end 43 of the wrapper interposed therebetween.

The wrapped container then proceeds to station K where the side margins 45 and 46 of the waxed wrapper are conventionally folded about the ends of the container and thence heat-sealed to each other and to flaps 21 and 22 to provide a substantially leakproof finished package.

The mechanical elements and equipment needed to perform various parts of the operations just described are in each instance conventional and may be purchased on the open market in any of several particular detailed forms. For this reason none of these elements have been shown in the drawings or described in detail. This invention resides not in the equipment used to form the package, but rather in the unique method by which the package is formed from the combined operation of several conventional items of equipment, and in the resulting package itself.

The finished package shown in small scale at station K of Figure 2 is further shown in Figure 3 in an initial stage of opening. In the formation of the package, opening panel 14 was not adhered to front panel 10 or to end 43 of wrapper 40, but the closure in this area was obtained by the heat-sealing adherence of end 43 of the wrapper to the exterior surface thereof at end portion 44 adjacent flap 14. It will be obvious that the remote end edge 29 (see Figure 1) of flap 14 provides a slight but definite protrusion or unevenness in the exterior surface of the complete package. Due to this feature, the fingernail or any relatively sharp instrument can be conveniently used to make an initial break in wrapper 40 to give access to the free edge 29 of flap 14. With a portion of edge 29 then accessible, flap 14 may be lifted, thereby tearing through wrapper 40 as indicated at tear lines 50, 51 and 52 in Figure 3.

As shown in Figure 4, continued lifting force applied to flap 14 will result in fracturing of wrapper 40 along the lines where it overlies hinge lines 25 and 26. The adherence of wrapper side margins 45 and 46 to flaps 21 and 22 is stronger than the connection between these flaps and panel 13, so that this lifting also results in severance of flaps 21 and 22 from cover panel 13 along the same hinge lines 25 and 26, the hinge lines providing substantial lines of weakness.

As shown in Figure 5, continued tearing of the outer wrapper along the junctures of the panels of the blank-receptacle results in a complete opening of the package

into flat condition, with resultant complete exposure of the contained product 4 for convenient access. Our method and package thus provide a substantially sealed container, made from a minimum amount of inexpensive materials, which can be formed and filled with conventional equipment at high speed.

While the above description sets forth details of a preferred form of our invention, certain elements of which might be modified in obvious fashion, it is to be understood that limitations on the invention are intended only as specifically set forth in the appended claims.

For example, the outer wrapper 40 may be inherently heat-sealable, or may be coated with a heat-sealable coating, so that sealing of the package may be accomplished by high speed conventional means.

We claim:

1. The method of forming a package, the package comprising a relatively flexible wrapper sheet and a relatively stiff paperboard blank divided by cut and score lines into a main panel, front and rear panels and main end flaps hingedly connected thereto, a cover panel hinged to the rear panel, and an opening flap and cover end flaps hinged to the cover panel, the method comprising erecting the main and cover panels perpendicular to said rear panel to form a receptacle with open ends and top, filling the material to be packaged into such receptacle in form commensurate with the dimensions of said blank, consecutively folding the main end and cover end flaps perpendicular to the main, cover and rear panels to close the ends of the receptacle, folding the front panel perpendicular to the main and cover panels and end flaps to close the top of the receptacle, applying one end of the wrapper to overlie said front panel, folding the opening flap to overlie said wrapper and folding the wrapper about the receptacle with the end portion thereof opposite said one end overlying and extending beyond the opening flap, adhering said opposite end to the exterior surface of the wrapper adjacent said opening flap, folding and adhering the side margins of said wrapper to enclose the end portions of the receptacle to form a substantially leak-proof package.

2. A method of forming a package according to claim 1, wherein said blank is supplied from a continuous roll thereof.
